UNITED STATES PATENT OFFICE.

CHARLES G. JOHNSON, OF HOUSTON, TEXAS.

WINDOW-SHADE.

1,330,268.

Specification of Letters Patent. Patented Feb. 10, 1920.

Application filed February 10, 1919. Serial No. 276,189.

To all whom it may concern:

Be it known that I, CHARLES G. JOHNSON, a citizen of the United States, residing at Houston, in the county of Harris and State 5 of Texas, have invented certain new and useful Improvements in Window-Shades, of which the following is a specification.

This invention relates to new and useful improvements in window shades.

10 One object of this invention is to provide a shade of the character described, including a novel method of securing the shade to the supporting shade roller.

Another object of the invention resides 15 in the provision of a window shade in combination with a supporting roller, the shade being secured to the roller by flexible straps whereby the shade is spaced a distance from the roller.

20 A further feature resides in the provision of means for supporting window shades, awnings and the like, from the supporting roller.

With the above and other objects in view, 25 the invention has particular relation to certain novel features of construction, arrangement of parts, and use, an example of which is given in this specification and illustrated in the accompanying drawings, 30 wherein:

Figure 1, is a perspective view of a window casing, with the improved form of shade attached thereto, and

Fig. 2, shows a fragmentary view of the 35 modified form of shade, showing the shade spaced a considerable distance from the supporting roller, so as to admit light and air above the shade.

Referring now more particularly to the 40 drawings, wherein like numerals of reference designate similar parts in each of the figures, the numerals 1, 1, refer to the sides of the window casing, said casing having the top 2, and the bottom 3. Secured in the usual manner to the top part of the casing above the window opening, is the shade roller 4, the well known spring roller 45 being preferably used. The numeral 5, re-

fers to the window shade, which is formed of fabric or any other suitable flexible material. This shade is suspended from the roller 4, by means of flexible straps 6. These straps are formed, at one end into circular loops or sleeves, which are fitted around the roller, and depend therefrom, and to their 50 lower ends they are sewed or otherwise secured to the upper edge of the shade, so as to space the shade the required distance from the roller, and if desired, may be formed of elastic material, so as to grip the 55 roller and to relieve the strain on them when the shade is pulled downwardly, and to permit the lateral swing of the shade when it is grasped at one corner to be lowered, as indicated in dotted lines in Fig. 1, thus distributing the strain to the straps 6, and lessening the likelihood of said straps being 60 torn from the roller or broken. The shade is thus securely fastened to the roller 4 and is not liable to be torn or detached therefrom when the shade is sufficiently lowered, 65 as is often the case with shades of this character as now constructed. The straps may be of any desired length, and in Fig. 2, they are shown of considerable length, so 70 that when the shade is completely lowered, light and air will be admitted above the shade, and at the same time, the lower part of the window will be protected by the 75 shade.

What I claim is:

The combination with a shade supporting roller, of a window shade spaced below the roller, and flexible straps formed of elastic material, one end of each strap being formed 80 into a loop which fits around and grips the roller, and the other end of each strap being fastened to the upper end of the shade.

In testimony whereof, I have signed my 85 name to this specification in the presence 90 of two subscribing witnesses.

CHARLES G. JOHNSON.
